UNITED STATES PATENT OFFICE.

WILLIAM T. ROBINSON, OF ETHEL, WEST VIRGINIA.

SAFETY APPLIANCE FOR STEAM-ENGINES.

1,132,795.

Specification of Letters Patent. Patented Mar. 23, 1915.

Application filed October 25, 1913. Serial No. 797,311.

To all whom it may concern:

Be it known that I, WILLIAM T. ROBINSON, a citizen of the United States, residing at Ethel, in the county of Logan and State 5 of West Virginia, have invented certain new useful Improvements in Safety Appliances for Steam-Engines, of which the following is a specification, reference being had to the accompanying drawings.

10 This invention comprehends certain new and useful improvements in safety appliances for steam engines and the like employed for operating electrical generators, and has for its primary object to provide a 15 steam separator having means for automatically cutting off the supply of steam to the engine and for operating a circuit breaker actuating member, when the water in the separating or water chamber of the 20 device rises above a predetermined level, and thereby prevent the water from entering the engine and at the same time break the circuit within which is positioned the electrical generator operated by said engine.

25 A further object is to provide a device of this character which will be of extremely simple construction and operation as well as highly efficient and effective in use and which will automatically stop the engine 30 and break the circuit by closing the throttle valve should more water be separated from the steam passing through the separator than can be properly handled by the trap to which the water from the separating or 35 water chamber of the device is conducted.

A further object is to generally improve and simplify the construction and operation of devices of this character and increase the efficiency of the same without materially 40 increasing the cost thereof.

With the above and other objects in view, my invention consists in certain novel constructions, combinations, and arrangements of parts to be hereinafter more fully described, claimed, and illustrated in the accompanying drawings, in which,

Figure 1 is a longitudinal section through the complete device; Fig. 2 is a cross-sectional view on the line 2—2 of Fig. 1; Fig. 3 50 is an enlarged detail section of the main valve and valve stem; Fig. 4 is an enlarged detail section of the auxiliary valve and casing for the same; and Fig. 5 is a detail longitudinal section of the circuit breaker 55 releasing means.

Referring more specifically to the draw-

ings in which similar reference characters designate corresponding parts throughout the several views, 1 designates the upper casting which has an upper vertical steam 60 passage 2 and a lower vertical steam passage 3 which are connected by a horizontal steam passage 4 having a vertical wall 5 with a valve opening 6 and a valve seat 7 around the edge of said opening. The 65 lower vertical steam passage 3 connects with the upper end of the curved steam passage 8 in the lower casting 9 the steam passage 8 having its lower end in communication with the upper end of the separator chamber 10. 70 The lower casting 9 also has a steam outlet passage 11, the lower end of which opens through the lower end of the casting, while the opposite end of said steam outlet passage connects with the upper portion of the 75 chamber 10, a baffle wall 12 being positioned in the steam outlet passage 11 and extending upwardly therein from the inner wall of the chamber 10, said baffle wall 12 having its upper end curved toward the inner wall 80 of the steam outlet passage 11, as shown at 13. The purpose of this construction will presently appear. The inner or partition wall 14 of the casting 9 has its upper end connected with the outer wall of the steam 85 outlet passage 11 adjacent the upper end of the latter and extends substantially parallel with the outer wall of the steam passage 8. The lower end of the wall 14, however, is bifurcated, thereby forming the 90 walls 15 and 16 at the lower end of the steam passage 8 and inner end of the steam passage 11. The lower end of the wall 15 is connected with the lower end of the outer wall of the steam passage 8 while the wall 95 16 forms the upper portion of the inner wall 17 of the chamber 10. It will also be understood that the wall 14 serves as the inner wall of the steam passage 8 and the walls 14, 16, and 17 constitute the inner 100 wall of the steam passage 11. It will also be understood that one longitudinal edge of each of the walls 15 and 16 is spaced from the adjacent walls of the casting 9, thereby permitting steam to pass over the 105 wall 15 when entering the chamber 10 and under the wall 16 when leaving said chamber, as will be clearly understood. It will further be understood that the lower end of the wall 12 is secured to the inner wall 110 of the chamber 10 at the point at which the walls 16 and 17 are connected. The

outer end of the chamber 10 is closed by the cap 18 secured in position in any suitable manner. A drain pipe 19 has one end secured in the bottom wall of the chamber 10 and serves to drain water from the chamber 10 to a trap (not shown) or to any other suitable point.

A shaft 20 is mounted transversely in the cap 18 and has one end projecting through 10 the same, with an arm 21 secured thereto by the set screw 22 or other suitable means, whereby the position of said arm 21 relatively to the shaft may be readily adjusted.

An arm 23 is also secured to the shaft 20, 15 within the cap 18 and has a float 24 secured upon its free end, within the chamber 10. It will be readily seen that as the float 24

raises and lowers, according to the amount of water in the chamber 10, the shaft 20 20 will be rotated to swing the arm 21 and thereby raise or lower latch bar 25 which has its lower end secured to the arm 21. The latch bar is formed in two or more sections 25

adjustably connected by the turn buckle 26, or the like, and the uppermost section 25' is directed inwardly toward the upper casting 1 and then directed upwardly with its upper extremity 27 reduced and adapted for engagement in the groove 28,

30 formed in the valve rod 29, near the outer end of the same, when the valve rod is in its innermost position and the latch bar 25 is in its uppermost position on account of the float 24 being in the lower portion of 35 the chamber 10. It will be understood that outward movement of the upper end of the upper vertically directed portion of the upper latch bar section 25' is prevented by engagement of said upper end of the vertical

40 portion with the roller 30 rotatably mounted on the main portion of the guide member 32, the arms of which are parallel and secured to the plate 33 which is removably fastened to the outer face of the casting 1.

45 The latch bar 25 has its upper end engaged in the guide member 32 and is thereby prevented from moving to the side as well as being prevented from moving outwardly past the roller 30.

50 The valve rod 29 is slidably engaged through a suitable bearing opening 34 and has a handle 35 mounted upon its outer end while its inner end is slidably mounted upon the guide pin 36 having one end secured in the head 37 which closes one end of the horizontal steam passage 4. An annular flange 38 is formed on the valve rod 29 near its last mentioned or inner end and a suitable valve 39 secured to one face thereof and 55 adapted for engagement against the valve seat 7. The valve rod 29 is forced outwardly and the valve 39 thereby forced against the valve seat 7 by means of a helical spring 40 or the like engaged around the 60 guide pin 36 and having one end bearing

against the head 37 while its opposite end bears against the internal circular flange 41 in the inner end of the valve rod 29. The valve rod 29 has an inlet port 42 leading from the interior of the valve rod to the exterior thereof, between the internal circular flange 41 and the external annular flange 38, the purpose of which will later appear.

The valve rod 29 has a second annular groove 43 in its outer end within which is 75 positioned a sleeve 44, to which in turn is pivoted a socket 45 having one end of a rod 46 adjustably secured therein, while the opposite end of said rod 46 is pivoted to an arm 47 mounted upon the stem of an auxiliary valve 48. From the casing 49 of the valve 48, the pipes 50 and 51 project in opposite directions and in alinement with one another, the pipe 50 being secured to the casting 1 in such manner as to receive 80 steam from the upper vertical passage 2 of said casting, while the pipe 51 leads to a cylinder 52 within which is positioned a piston 53. The piston 53 is secured upon one end of a piston rod 54 which projects 85 through the upper end of the cylinder 52 and has the breaker releasing button 55 adjustably secured upon its upper end for engagement with a circuit breaker to release the same and thereby break the circuit, 90 when the piston 53 is forced upwardly in the cylinder 52 by steam fed to said cylinder by the pipe 51. The piston 53 is normally retained in the lower end of the cylinder 52 by a coil spring 56 engaged around the piston rod 54 within the cylinder 52. It will be understood that a suitable waste pipe 57 is secured on the cylinder 52. A drain pipe 58 also projects from the valve casing 49, said pipe extending at right 95 angles to the pipes 50 and 51. The valve 48 may be of any suitable form but is preferably provided with a straight transverse passage 59 which connects the pipes 50 and 51 and allows steam to pass through said pipes to the cylinder 52 to raise the piston 53 when the valve 39 closes and the valve rod 29 moves outwardly, thereby operating the rod 46 and arm 47 to swing the auxiliary valve 48 to the position shown in Fig. 115 1. When the valve 39 is opened by forcing the valve stem 29 inwardly, the rod 46 and arm 47 are moved in opposite directions, thereby turning the valve 48 so that its right angled passage 60 connects the 120 pipes 51 to 58 and moves the straight transverse passage 59 out of alinement with the pipes 50 and 51, thereby preventing steam from passing from the pipe 50 and the pipe 51 and allowing the steam within the pipe 125 51 and cylinder 52 to pass from the same through the right angled passage 60 to the drain pipe 58, thereby allowing the spring 56 to force the piston 53 and piston rod 54 downwardly to their normal positions. The 130

upper vertical passage 2 is connected with the lower vertical passage 3 of the casting 1 by the pipe 61, which will be hereafter referred to as the by-pass.

5 It will be understood that the connected castings 1 and 2 are placed in the path of the steam supply pipe, thereby compelling the steam to pass through the separator on its way to the cylinders of the engine. The 10 valve 39 is normally in open position and the steam passes through the valve opening 6 and along the steam passages 3 and 8 to the water or separating chamber 10. The steam then passes out of the chamber 10, 15 under the wall 16, around the turned end 13 of the partition wall 12, and out of the passage 11, while the water from the steam is deposited in the water or separating chamber 10. Should the water bank up in the 20 chamber 10, the float 24 will be caused to rise, thereby drawing down the latch bar 25 and releasing the valve rod 29 as previously described, allowing the valve rod 29 and valve 39 to move outwardly until said valve 25 39 is properly engaged against the valve seat 7. A sufficient quantity of steam will pass into the hollow portion of the valve rod 29 by way of the inlet port 42 and press against the end wall 62 of the hollow portion of said valve rod 29 and thereby assist the spring 40 in retaining the valve 39 in closed position. While the valve is closed, however, a sufficient amount of steam will pass through the by-pass 61 to fill the steam 30 35 passages 8 and 3 and the end of the horizontal steam passage 4 connected with said passage 3 and thereby practically equalize the pressure against the opposite side of the valve, thereby making it possible to readily reopen the valve by simply exerting enough pressure against the outer end of the rod 29 to overcome the resistance of the spring 40.

From the foregoing, it will be clearly apparent that I have provided an automatic steam and water separator which will be highly efficient and effective in use and which will automatically cut off the flow of steam to the cylinders of the steam engine 40 45 and break the circuit within which is con-

nected an electrical generator operated by the engine should there be too much water mixed with the steam or should the operation of the engine be discontinued for any reason whatever.

55 While I have shown the preferred embodiment of my invention, it will be understood that minor changes in the details of construction and arrangement of parts may be made within the scope of the appended 60 claim without departing from the spirit of my invention or sacrificing any of the advantages of the same.

What I claim is:—

A device of the class described including 65 a body casting having a central vertical wall therein provided with an opening, said casting having chambers arranged upon opposite sides of the central wall and having communication through the opening, a reciprocating valve rod mounted in one side of the casting, a valve carried by said rod and adapted to close the opening in the central wall, a guide pin slidably received within one end of the valve rod which has its 70 outer end mounted in one wall of the casting, a coil spring upon said guide pin adapted to bear against the inner end of the valve rod to retain the valve in its closed position, the outer end of said valve rod having an 75 annular groove therein, a separating chamber within the lower end of the body casting, a float therein, a crank shaft connected with the float, a latch bar having one end connected with the crank shaft and the other 80 end adapted for engagement within the groove in the valve rod to normally retain the valve in an open position against the tension of said spring, and said float being adapted to actuate the latch bar to disengage the same from the groove, and permit of outward reciprocation of the valve rod 85 to close the valve.

90 In testimony whereof I hereunto affix my signature in the presence of two witnesses. 95

WILLIAM T. ROBINSON.
